ABSTRACT

A log-periodic antenna comprises two arrays of dimensionally tapered radiating elements disposed in the E-plane and each fed by a balanced line consisting of the inner conductors of two coaxial cables. In one embodiment the elements of each array are dipoles and in an other embodiment are formed of continuous conductive strips in zig-zag patterns on non-conductive support members. Each array preferably has two sets of elements disposed in planes, respectively, which converge toward the smaller end of the array with vertically aligned radiating elements of each set projecting in opposite directions from the array axis. Periodic gain dropout anomalies across the antenna operating band are at least substantially reduced by use of shielded feed lines. In another embodiment which has particular advantage at HF frequencies, a single array is operated over a ground plane which provides a mirror image thereof. In yet another embodiment which has advantage in direction finding, the sets of elements of each array are located on associated opposite sides of a right rectangular pyramid. A pair of these pyramidal arrays, with some of the element sets being coplanar, are employed for direction finding.

GROUNDPLANE MOUNTED LOG-PERIODIC ANTENNA

RELATED APPLICATION

This is a continuation-in-part of Ser. No. 309,874, filed Oct. 9, 1981, now abandoned.

BACKGROUND OF THE INVENTION

This invention relates to frequency independent antennas and more particularly to frequency independent log-periodic antenna arrays.

Log-periodic antennas, well known for their pseudo-frequency independent operation, are arrayed together to provide higher directivity and higher gain and also to adapt the antennas for use in direction finding and tracking applications. Such uses of arrayed log-periodic antennas provide independent error curves for either amplitude comparison or for sum and difference derivations. A problem with such arrays is the periodic occurrence of gain variations in the E-plane arrays of the antenna across the operating band. These periodic gain variations or "dropouts" are accompanied by pattern deteriorations and seriously adversely affect the performance of the antenna. When a pair of conventional log-periodic dipole antennas were arrayed in the frequency independent manner with coplanar elements of the antennas in the E-plane, periodic gain dropouts of more than 10 dB over an active operating band were measured in spite of the fact that the individual antenna elements of the array provide frequency independent operation. The elements are arranged in a frequency independent manner when lines through the end points of the elements intersect at a common point, the apex of the antenna.

Attempts to decrease or eliminate such gain dropouts and pattern deteriorations have been made in the past. By using size-reduced dipoles as radiating elements as described in U.S. Pat. No. 3,732,572, the magnitudes of the gain dropouts have been reduced but not completely eliminated. Another technique that has been proposed is wrapping of the two-wire transmission line with RF absorbing material, see "A Study of TEM Resonances on a Class of Parallel Dipole Arrays" by Tranquilla et al, Proceedings of the 1977 Antenna Applications Symposium, Electromagnetics Laboratory, University of Illinois, Urbana Champaign, Ill., Apr. 27-29, 1977. Such absorbing materials, however, produce substantial losses of approximately 4 to 6 dB at all frequencies and therefore are not an acceptable solution to the problem.

OBJECTS AND SUMMARY OF THE INVENTION

A general object of the invention is the provision of a log-periodic antenna having arrays of elements operating over the frequency band of the antenna with at least substantially reduced gain dropouts.

These and other objects of the invention are achieved by utilizing a shielded balanced feed line for energizing log-periodic antenna elements arrayed in a frequency independent manner. A preferred form of the shielded feed line comprises the inner conductor of a coaxial cable.

DESCRIPTION OF THE DRAWINGS

FIG. 1 is a schematic plan view of a log-periodic dipole antenna embodying this invention.

FIG. 2 is a perspective view of one of the arrays of FIG. 1 with parts of the feed lines broken away to show details of construction.

FIG. 3 is a schematic plan view similar to FIG. 1 showing arrays having a zig-zag pattern of radiating elements.

FIG. 4 is an enlarged perspective view of one of the arrays of FIG. 3.

FIG. 5 is a greatly enlarged portion of FIG. 4 showing the connection of the feed lines to the radiating elements.

FIG. 6 is a greatly enlarged plan view of a portion of the zig-zag shaped conductive strip of FIGS. 3-5 showing design parameters.

FIG. 7 is a perspective view of an array of a log-periodic antenna designed for circularly polarized operation and embodying the invention.

FIG. 8 is an enlarged end view of the array taken on line 8-8 of FIG. 7.

FIG. 9 is a schematic representation of two of the arrays of FIG. 7 disposed to provide direction finding information.

FIG. 10 is a schematic plan view of a log-periodic dipole antenna incorporating an alternate embodiment of this invention.

FIG. 11 is a schematic plan view of a zig-zag antenna incorporating an alternate embodiment of this invention.

DESCRIPTION OF PREFERRED EMBODIMENTS

Referring now to the drawings, FIG. 1 illustrates an antenna 10 embodying the invention and comprising dipole arrays 11 and 12 in a horizontal (E) plane, the axes 13 and 14 of arrays 11 and 12, respectively, forming an angle ϵ . Arrays 11 and 12 have feed lines 16 and 17, respectively, connected to hybrid T junctions 18 and 19, respectively, also known as magic T junctions. The outputs of the magic T junctions 18 and 19 are connected to a power divider 21 which in turn is connected to utility apparatus such as a receiver or transmitter.

Antenna arrays 11 and 12 are substantially identical in construction and accordingly only one of them, array 11, is shown in FIG. 2 and is described. Feed line 16 of array 11 comprises vertically stacked coaxial cables 23 and 24 having inner conductors 25 and 26, respectively, and outer conductors 27 and 28, respectively. The outer conductors are grounded as indicated at 29 and thus shield the inner conductors. Cables 23 and 24 are connected to magic T 18 which provides 180° phase reversal in the two lines as required for end fire radiation along array axis 13.

Radiating elements 30 are connected to the feed lines transversely of the array axis 13 such that element dimensions and interelement spacings decrease from a maximum at one end to a minimum at the other in increments dictated by a predetermined ratio τ , where $\sqrt{\tau}$ is the ratio of the spacing between the intersection point A in FIG. 1 and one dipole, and that to the adjacent longer dipole (e.g. l₁/l₂ in FIG. 6). These elements comprise a first set a, b, c, d and e connected to inner conductor 25 of cable 23 and a second set a', b', c', d' and e' connected to inner conductor 26 of cable 24. Each element extends through an opening in the outer conductor of the associ-

ated cable for direct electrical contact with the inner conductor thereof. The elements of each array are arranged in transversely extending pairs, each pair being designated by the same letter a—a', b—b', etc., and each pair comprising one dipole. Inner conductors 25 and 26 are the balanced feed lines for the array and by connecting them to the radiating elements and by grounding outer conductors 27 and 28 as described, the feed lines are shielded from external radiation including the effects of mutual coupling between arrays 11 and 12. By use of these shielded feed lines, periodic gain variations across the operating band of the antenna are significantly reduced, if not eliminated.

A log-periodic dipole antenna 10 constructed as described above had the following design parameters and performance characteristics:

Convergence angle ϵ	26°
Taper angle α	20°
τ	0.9
Smallest dipole	5"
Largest dipole	16"
Feed line impedance (Z_0) 100 ohms	
Frequency band	470-900 MHz

The feeder impedance is 100 ohms because 50 ohm coaxial cables were used. This antenna provided pseudofrequency independent performance similar to a log-periodic dipole antenna fed by conventional balanced lines. When two dipole arrays were arranged in the frequency independent manner at relatively close spacing, i.e., 0.5 wavelength between the axes of radiating dipoles, the antenna provided substantially frequency independent performance with no measurable periodic gain dropouts or pattern deteriorations. The dipole antenna described above is readily constructed to operate at UHF frequencies but is not easily operated at microwave frequencies due to the physical size of the balun at the front of the antenna and the manner in which the radiators are attached to the transmission lines.

Additionally, an antenna 10' in FIG. 10 having electrical characteristics similar to the antenna 10 of FIG. 1 may be fabricated by locating an array 11', for example, over a ground plane 80 which includes the line B—B in FIG. 1 and is orthogonal to the plane of the paper. A mirror image 12' of the array 11' is formed in the ground plane and satisfies the function of the second array 12 in FIG. 1. Such a ground plane mounted antenna 10' has particular advantage for high frequency (HF) communications in the range of 2-32 MHz since it requires only half of the hardware and provides the gain of two antennas. An electrically conductive ground plane is preferably placed under the log-periodic dipole array 11' to reduce ground loss. Since the dipole array for a log-periodic antenna operating over a ground plane is normally fabricated with the distance between the active region of the antenna and the ground plane as a constant with respect to the operating frequency, i.e., oriented in a frequency independent manner, there are periodic gain dropouts even though only one antenna array is actually excited. In order to significantly reduce or eliminate these gain dropouts, the feed lines for and the structure of the array 11' is the same as that in FIG. 2, except that the output of magic T 18 in FIG. 10 is connected to a utilization device (i.e., the antenna 10' does not require a power divider 21).

The shielded feed lines described above as being the inner conductors of coaxial cables in FIGS. 1 and 2

achieve the objects of this invention efficiently and economically since standard commercially available cable is utilized. Practice of the invention, however, is not limited to this feed line. Alternatively, the feed line 5 may take the form of twin spaced conductors within a single enclosing grounded shield having openings through which the dipoles extend for connection to the lines as described above.

Periodic gain dropouts and pattern deteriorations are 10 not limited to E-plane arrays of the planar log-periodic dipole antennas of the type described above. Open structure types of log-periodic antennas comprising E-plane arrays with the radiating elements of each array in two planes intersecting at the feed point also have 15 periodic gain dropouts when arrayed in the frequency independent manner. An example of such open type structure is illustrated in FIGS. 3 and 4 and comprises antenna 35 having substantially identical arrays 36 and 37, each array having two sets of planar radiating elements oriented at an angle Ψ in the H-plane. The angle Ψ determines the H-plane beamwidth and the mean level of the input impedance of the antenna and distinguishes the "open" structure from the planar antenna. In other words, when the angle Ψ approaches 0, a planar antenna comparable to the above described planar log-periodic dipole antenna results. Additionally, the planes containing the sets of elements of the log-periodic dipole antenna of FIGS. 1 and 2 may be located at 20 an angle to form an open structure type of antenna.

Arrays 36 and 37 have axes 38 and 39, respectively, 25 which intersect at an angle θ toward the feed points of the arrays, and in accordance with this invention, are fed by balanced lines 41 and 42, respectively. These arrays are substantially identical and accordingly only one of them, array 36, is described. Feed line 41 comprises the inner conductors 43a and 44a of coaxial cables 43 and 44, respectively, see FIGS. 4 and 5. Cables of lines 41 and 42 are connected to magic T couplers 45 and 46, respectively, which in turn are connected to a power divider 47 for connection to associated utility apparatus. Array 36 comprises a pair of conductive strips 50 and 51 in tapered zig-zag shapes forming generally triangularly shaped radiating elements. Strips 50 and 51 are mounted on elongated support members 52 and 53, respectively, composed of dielectric material such as epoxy fiberglass. The outer conductors of coaxial cables 43 and 44 are suitably grounded and the inner conductors 43a and 44a thereof are connected to strips 50 and 51, respectively, at the converging end of the array to constitute the feed point.

The triangular portions of strips 50 and 51, having the 30 same spacing from the array feed point, project equal distances and in opposite directions from supports 52 and 53, respectively, and constitute the radiating elements of the array. For example, segment 50a of strip 50 and segment 51a of strip 51 are equally spaced from the feed point and project equal distances and in opposite directions from supports 52 and 53, respectively. Segments 50a and 51a thus have equal lengths and constitute one radiating element of the array analogous to a dipole of array 11.

The continuous zig-zag shaped conductive strip is 35 defined by two conventional log-periodic design parameters α (see FIG. 6) and τ . An additional design parameter β defines the width of the zig-zag conductor. When the value of β approaches the value of α , the antenna structure approaches that of a zig-zag wire. As

the value of β decreases, the width of the zig-zag conductor increases until β approaches 0. The array structure consisting of two of these zig-zag conductors performs similarly to the conventional log-periodic dipole array with the exception of a slight loss of gain due to the I^2R loss. The exciting currents, instead of travelling straight on the metallic boom of the conventional antenna, follow the zig-zag conductor path before reaching the active region of the array. The loss is less than 1 dB. By decreasing the angle β this loss is minimized with the tradeoff of a slight increase in the amount of conductive material. The spacings $l_0, l_1, l_2, \dots, l_n$ of the elements from the point of convergence as illustrated in FIG. 6 are related to each other log-periodically in accordance with the following formulae:

$$l_0 = \sqrt{\tau} l_1$$

$$l_1 = \sqrt{\tau} l_2$$

$$l_{n-1} = \sqrt{\tau} l_n$$

A circularly polarized antenna embodying the invention was constructed by substituting a 90° coupler for the power divider 47 in FIG. 3 and such antenna had the following parameters:

$$\alpha = 20^\circ$$

$$\beta = 7^\circ$$

$$\sqrt{\tau} = 0.9$$

Length of smallest element 0.3"
Length of largest element 7.0"
Frequency band 1 to 12 GHz

No periodic gain dropout anomalies were observed during operation of the above antenna.

Also, an antenna 35' in FIG. 11 having electrical characteristics similar to the antenna 35 in FIG. 3 may be fabricated by locating an array 36' over a ground plane 85 which includes the line C—C in FIG. 3 and is orthogonal to the plane of the paper. A mirror image 37' of the array 36' is formed in the ground and satisfies the function of the second array 37 in FIG. 3. The array 36' is preferably fed with the shielded-balanced feed structure in FIGS. 4 and 5, where the output line 45' of the magic T 45 (in FIG. 11) is connected to a utilization device (i.e., the power divider 47 is no longer required). Alternatively, in an HF application where the size of the triangular portion or radiating elements of the antenna are very large compared to the size of the balun or magic T 45, the balanced feed line 41 (which comprises coaxial cables 43 and 44) may be eliminated and the magic T 45 connected directly to the small or feed point ends of the strips 50 and 51, or even located in front of the strips. Additionally, the angle Ψ is preferably reduced to substantially 0° in an HF application for conserving real estate and reducing the complexity of the antenna. Also, the radiating elements of the zig-zag antenna 35' may be outlined with electrically conductive wire such as along lines 91 and 92 in FIG. 6, rather than being formed out of sheet metal, for reducing the weight and wind resistance of the structure.

Another embodiment of the invention is shown in FIGS. 7, 8 and 9 depicting a circularly polarized antenna array 55 comprising four zig-zag conductive

strips 56, 57, 58 and 59, similar to the strips shown in FIG. 6 and mounted on the plane sides of a right rectangular pyramid-like dielectric support 60. Adjacent sides of support 60 are at right angles to each other and taper from a maximum dimension at one end to a minimum dimension at the other. Each of the strips is similarly tapered to the feed point of each at the end having the minimum dimension. The planes of adjacent strips are likewise perpendicular to each other as shown in FIGS. 7 and 8.

The array 55 is fed by the inner conductors 62, 63, 64 and 65 of coaxial cables, the outer conductors of which are connected to ground. Cables having conductors 62 and 64 are connected to magic T 67 and cables having conductors 63 and 65 are connected to magic T 68. Each magic T is connected to a 90° coupler 69 which in turn is connected to associated utility apparatus. The magic T junctions 67 and 68 and the 90° coupler 69 are enclosed in a broken line block 70 for convenience of explanation of FIG. 9. When two such circularly polarized arrays 55 and 55' are arrayed together as shown in FIG. 9, the outputs of block 70 and identical block 70' may be combined in magic T 71 to provide direction finding data. If two pairs of zig-zag strips are in a common E-plane when the structures are arrayed as shown in FIG. 9, the antenna is subject to the gain dropout anomaly when energized by conventional unshielded feed lines. In accordance with this invention, the use of shielded feed lines for each of the array structures shown in FIG. 9 at least substantially reduces this gain dropout anomaly.

An antenna shown in FIGS. 7, 8 and 9 was constructed and operated from 0.25 to 4.0 GHz. The smallest and largest radiating elements were 0.8 inches and 26 inches, respectively. This frequency independent array was used as a direction finding antenna and operated over the above band without any measurable periodic gain dropout anomaly.

What is claimed is:

1. A log-periodic dipole antenna comprising:
a ground plane,
an array of radiating elements, said array having an axis and comprising first and second sets of said elements, each of said sets of elements having an axis, the elements of each set having lengths and interelement spacings decreasing axially from a maximum at one end to a minimum at the other end in increments at a predetermined ratio, adjacent elements of each set extending on opposite sides of the axis of the set and forming dipoles, and
balanced feed means for energizing said elements comprising first and second lines and means to shield said lines, said shield means being connected to the ground reference potential of the ground plate,
the elements of said first set being connected to said first line and the elements of said second set being connected to said second line,
each element of said first set having a length equal to the length of a corresponding element of said second set and being axially spaced from said other end by the same distance as said corresponding element, with elements of equal length of said sets extending in opposite directions,
said array being located over said ground plane for creating a mirror image,

said array elements being arranged in an E-plane, in a frequency independent manner, and to be coplanar with corresponding mirror image elements.

2. The antenna according to claim 1 in which said feed means comprises a pair of coaxial cables, said lines being the inner conductors of said cables, said shield means comprising the outer conductors of said cables.

3. The antenna according to claim 2 wherein all of said outer conductors are connected to the common ground reference potential of the ground plane.

4. The antenna according to claim 2 in which planes containing elements of said first and second sets form an acute angle with each other.

5. The antenna according to claim 2 wherein planes containing elements of said first and second sets are adjacent and parallel to each other.

6. The antenna according to claim 2, wherein planes containing elements are orthogonal to said ground plane.

7. The antenna according to claim 6 wherein one end of each radiating element is electrically connected to the associated inner conductor along the length of the latter.

8. A log-periodic antenna comprising an array of radiating elements, said array having an axis and comprising

a ground plane, first and second sets of generally triangularly shaped radiating elements in associated planes with adjacent elements extending in opposite directions from an axis thereof in the associated plane; said elements being arranged in a frequency independent manner and in an E-plane;

first and second dielectric means for supporting said first and second sets in associated planes, each of said sets of elements having an axis, the elements of each set having lengths and interelement spacings decreasing axially from a maximum at one end to a minimum at the other end in increments at a predetermined ratio, adjacent elements of each set extending on opposite sides of the axis of that set; each element of the first set having a length equal to the length of a corresponding element of the second set and being axially spaced from said

other end by the same distance as said corresponding element; elements of equal length of said sets extending in opposite directions; and shielded feed means for energizing said elements: said array being located over said ground plane for creating a mirror image array with array elements coplanar with corresponding mirror image elements.

9. The antenna according to claim 8 wherein said shielded feed means comprises first and second lines and means to shield said lines.

10. The antenna according to claim 9 wherein the radiating elements of each of said sets comprises an associated planar conductive means having a generally zig-zag configuration.

11. The antenna according to claim 10 wherein each of said planar conductive means comprises a continuous conductive strip.

12. The antenna according to claim 10 wherein planes containing elements of said first and second sets form an acute angle with each other.

13. The antenna according to claim 11 wherein said feed means is connected to said conductive strips adjacent the end thereof defining the shortest radiating elements.

14. The antenna according to claim 10 wherein each of said planar conductive means comprises a pair of continuous electrically conductive wires extending in a zig-zag manner over the length of the array for outlining in the associated plane generally triangularly shaped elements extending on opposite sides of the axis of the associated set.

15. The antenna according to claim 9 wherein said feed means comprises a pair of coaxial cables having inner conductors which comprise said first and second lines and outer conductors which comprise said shield means.

16. The antenna according to claim 15 wherein said outer conductors are connected to the common ground reference potential of the ground plane.

17. The antenna according to claim 9 wherein said shield means is connected to a ground reference potential.
